[57] CLAIM

The ornamental designs for a keypad for a security system, as shown and described.

DESCRIPTION

FIG. 1 is a front elevational view of a keypad for a security system showing my new design;

FIG. 2 is a right side elevational view thereof, with the left side being a mirror image, except for the width of the read-out shield;

FIG. 3 is a perspective view thereof;

FIG. 4 is a front elevational view of a second embodiment, wherein the only difference resides in the appearance of the keys;

FIG. 5 is a right side elevational view thereof, with the left side being a mirror image, except for the width of the read-out shield;

FIG. 6 is a perspective view thereof;

FIG. 7 is a front elevational view of a third embodiment wherein the only difference resides in the appearance of the keys;

FIG. 8 is a right side elevational view thereof, with the left side being a mirror image, except for the width of the read-out shield; and,

FIG. 9 is a perspective view thereof.
